UNITED STATES PATENT OFFICE

ALFRED L. HARRINGTON, OF ROSSLYN FARMS, PENNSYLVANIA, ASSIGNOR TO PITTSBURGH PLATE GLASS COMPANY, A CORPORATION OF PENNSYLVANIA

FLUID COOLED ROLL

Application filed August 13, 1930. Serial No. 474,893.

The invention relates to fluid cooled rolls for use in glass rolling apparatus. The invention has for its principal objects the provision of an improved roll in which the tendency of the roll to warp under the severe heat conditions encountered in forming glass sheets in an intermittent rolling operation is reduced to a minimum. Certain embodiments of the invention are illustrated in the accompanying drawings, wherein:

Figure 1 is an assembly view in vertical cross section taken on the line I—I of Fig. 2 showing the roll in position of service. Fig. 2 is a partial front elevation and partial section on the line II—II of Fig. 1. Figs. 3 and 4 are enlarged detail sections through the roll, Fig. 3 being a section on the line III—III of Fig. 4, and Fig. 4 being a section on the line IV—IV of Fig. 3. Figs. 5, 6 and 7 illustrate a modification, Figs. 5 and 6 being sections, and Fig. 7 being a partial plan view. Figs. 8 and 9 are sections illustrating another modification. And Figs. 10 and 11 are sections illustrating still another modification.

Figure 1 illustrates the application of the roll to an intermittent rolling apparatus, the glass sheet 1 being formed between the rolls 2 and 3, the latter of which being the structure to which the present invention is directed. The rolls are suitably driven, the roll 2 being supported upon the driven rolls 4 and 5. The body of glass 6 which forms the sheet is teemed into a pocket between the two rolls. One of the difficulties encountered in a rolling operation of this kind is that of maintaining the roll 3 at a proper temperature to prevent warping due to the fact that the application of a large body of molten glass on one side of the roll tends to distort it. As a result, the roll bows to a certain extent and the glass sheet which is formed is of uneven thickness. Due to this fact, the sheet must be cast somewhat thicker than would otherwise be the case and more grinding is required to bring the two faces of the sheets to parallelism throughout. The present invention is designed to overcome this difficulty and to reduce any bowing or warping to a minimum.

The roll 3 preferably consists of a series

of annular discs 7 brazed together at their side faces so as to form a cylinder through which a circulation of water is provided by means of the swivels 8, 8 connected to suitable water supply pipes 9. The brazing is preferably done by the use of copper as a brazing material in a hydrogen furnace, the copper being supplied in the form of thin discs between the parts to be joined, or by plating the parts to be joined with copper preliminary to bringing them to a temperature necessary for brazing in a hydrogen furnace. The discs are each preferably reduced in thickness at their outer edges, as indicated in Fig. 3 so that a series of circumferential slots 10 are provided. These slots are preferably of such small width that the molten glass will not flow into and fill them during the rolling operation. This width may vary somewhat, but is preferably about one one-hundredths of an inch. By this expedient, any warping due to the roll being overheated on one side is reduced to a minimum since each disc can expand longitudinally of the roll without affecting the other discs. In order to still further overcome any tendency to warp, the surface of the roll is provided with the series of longitudinal slots 11 (Fig. 4). The surface of the roll is thus divided into a plurality of rectangles and each rectangular section as thus provided is free to expand without affecting any other section. These longitudinal slots are also preferably about one one-hundredths of an inch in width. They extend inward from the surface of the roll to about the same depth as the slots 10, as indicated in Figs. 3 and 4.

Figs. 5, 6, and 7 illustrate a modification in which the rolling face of the roll is made up of a plurality of pins or pegs 12 square in cross section and provided with reduced ends 13 which fit into sockets 14 in the cylinder 15. The pins are arranged so that their side walls are spaced away from each other, thus providing the circumferential grooves 16 and longitudinal grooves 17 corresponding to the grooves 10 and 11 of the construction of Figs. 1 to 4. The ends 13 of the pins may be shrunk in the sockets 14 or may be pressed in such sockets.

Figs. 8 and 9 illustrate another modification in which the roll is an integral structure. This roll, as in the other forms of construction is provided with two sets of slots 18 and 19, such slots being formed by saws or other suitable means. These slots extend in from the surface of the roll, preferably about 2 inches as in the other form of construction.

In the modification of Figs. 10 and 11 a central supporting cylinder 20 is used upon which is mounted a series of rings 21. These rings are brazed to each other along their side edges and also brazed to the cylinder 20. The rings are spaced apart by the slots 22 the same as in the construction of Figs. 1 to 4 and these rings are also provided with longitudinal slots 23 corresponding to the slots 11 in the construction of Figs. 1 to 4.

What I claim is:

- 20 1. A glass forming or sizing roll with a cooling passage extending through its center longitudinally thereof and having its surface provided with two series of slots one of which extends circumferentially of the roll at spaced intervals and the other of which extends longitudinally of the roll at spaced intervals transversely of the first series, said slots being of relatively small width so that the glass will not flow into and fill them.
- 25 2. A glass forming or sizing roll having a centrally located cooling passage comprising a series of annular discs arranged in series side by side and brazed together, the surface of said roll being provided with a series of spaced slots extending longitudinally thereof and of relatively small width so that the glass will not flow into and fill them.
- 30 3. A glass forming or sizing roll having a centrally located cooling passage comprising a series of annular discs arranged in series side by side and brazed together, said roll having its surface provided with two series of slots one of which extends circumferentially of the roll at spaced intervals and the other of which extends longitudinally of the roll at spaced intervals transversely of the first series, said slots being of relatively small width so that the glass will not flow into and fill them.
- 35 4. A glass forming or sizing roll having a centrally located cooling passage comprising a series of annular discs arranged in series side by side and brazed together, the surface of said roll being provided with a series of spaced slots extending circumferentially thereof and of relatively small width so that the glass will not flow into and fill them.
- 40 5. In combination in a roll, an inner supporting cylinder, means for circulating a cooling fluid through the cylinder, and a jacket secured to the cylinder and comprising a plurality of discs contacting with each other at their inner edges and brazed together, but spaced apart slightly at their peripheries, each of said discs being provided with a

series of spaced slots of small width extending longitudinally of the roll.

6. In combination, an integral metal cylinder, and means for circulating a cooling fluid therethrough, said cylinder having its surface provided with two series of slots one of which extends circumferentially of the roll at spaced intervals and the other of which extends longitudinally of the roll at spaced intervals transversely of the first series, said slots being of relatively small width so that the glass will not flow into and fill them.

In testimony whereof, I have hereunto subscribed my name this 4th day of August, 1930.

ALFRED L. HARRINGTON.
